UNITED STATES PATENT OFFICE.

ALFRED WALTER ROOVERS, OF BROOKLYN, NEW YORK.

GAGE FOR POSITIONING SHEETS IN EMBOSMING-PRESSES.

1,163,464.

Specification of Letters Patent.

Patented Dec. 7, 1915.

Application filed July 23, 1914. Serial No. 852,723.

To all whom it may concern:

Be it known that I, ALFRED W. ROOVERS, a citizen of the United States, residing at Brooklyn, in the county of Kings and State 5 of New York, have invented certain new and useful Improvements in Gages for Positioning Sheets in Embossing-Presses, of which the following is a specification.

My present invention pertains to an improvement in gages for positioning sheets or cards in embossing presses, the construction and advantages of which will be hereinafter set forth, reference being had to the annexed drawings, wherein:

Figure 1 is a side elevation of a die-press showing the gage applied thereto; Fig. 2 a top plan view, the operating lever being broken away to more clearly illustrate the underlying parts, and a portion of the gage 15 structure being shown in section; Fig. 3 a perspective view of the gage; Fig. 4 a perspective view of one of the clamping members shown in flat form just prior to its being brought to the final folded or shaped 20 position; Fig. 5 a side elevation, parts being broken away, showing a modified form of means for securing the gage to the press; and Fig. 6 a top plan view thereof, partly 25 in section.

The main object of the present invention is to provide a simple gage which may be attached to a die-press of the type shown and described in my co-pending application filed on or about the 23rd day of July, 1914, 30 Serial No. 852,722, the gage being so constructed that it may be adjusted to operate with different-sized embossing dies, and to properly position and hold the cards or sheets of various sizes and in different positions with relation to the dies, whereby the matter to be embossed may be placed at any desired point upon the card, sheet or the like.

In order that the invention may be readily understood without direct reference to the application above mentioned, I will give an outline description of the press, which may be said to comprise a relatively narrow frame 1, supported upon a laterally-extending 45 base 2, and provided at its forward portion with a transverse slot or opening 3, adapted to house the die-carrying arms 4 and 5, connected to each other at the rear by an integrally-formed loop 6. The dies

are designated by 7 and 8, and presser or 55 sustaining plates 9 and 10 overlie the dies, the lower plate 9 being rigidly secured to the frame. A lever 11, fulcrumed at 12 upon the frame, forces the upper plate 10 and the underlying die 8 downwardly. A card, designated 60 as 13, is shown in position (in Figs. 1 and 2) between the dies, said dies being closed down upon the card in the act of securing the desired embossment. In order to properly position said card, I employ gage 65 arms, one arm 14, being provided at its forward end with a downwardly-projecting stop member 15, and a forwardly-extending finger 16, the upper face of which finger, when the parts are properly adjusted, lies 70 in the plane of the upper face of the lowermost die 7. A second arm, 17, provided with a downwardly-extending stop member 18, is arranged upon the opposite side of the press, 75 said arm likewise having formed as an integral portion thereof a forwardly-extending member 19, corresponding in position and function to the finger 16. The member 19 carries at its forward end a lateral extension 20, from which there projects upwardly 80 a side gage finger 21. The various elements of the gage arm 17 are preferably formed integrally from a piece of square wire or bar, and may be readily bent to shape.

Secured to the rear of the frame 1 is a 85 sustaining casting or member, consisting of a main body portion 22, having a transverse opening formed therein and preferably square, from which member 22 extend outwardly two arms 23 and 24, the arm 23 90 being provided at its outer end with a bearing plate 25, while the opposite arm, 24, carries a screw 26 adapted to force the bearing member 25 into contact with a web-shaped member of the frame 1 when the screw is 95 turned up and bears against said frame member. A sustaining member 27, which is 100 preferably square in cross-section, passes through the opening in the member 22, and may be moved endwise therein and secured in its adjusted position by a wing-screw 28. Mounted upon each end of said sustaining bar is a combined supporting and clamping member for the gage arms 14 and 17. Said members are alike and are produced from a 105 single piece of sheet metal, bent to form, which may be said to comprise a top plate 29, having a threaded opening therein for

the reception of a binding-screw 30, and oppositely-disposed, downwardly-projecting plates 31 and 32, each provided with an opening 33, which openings are in alignment with each other and through which the sustaining bar 27 is designed to be passed. A second pair of downwardly-projecting plates, 34 and 35, are likewise provided with openings 36, which openings stand in alignment and in a plane slightly higher than that of the openings 33, so that the gage arms 14 or 17, as the case may be, when passed through the openings 36, will overlie the bar 27 and stand beneath the lower end of the screw 30. The openings 36 are somewhat elongated in their vertical direction, in order that the gage arms may have a slight vertical play therein, whereby, when the screws 30 are turned down, the gage arms 20 will be forced downwardly and into binding contact with the sustaining bar 27, which bar makes a relatively close fit with the openings 33 through which it passes. It will thus be seen that the combined supporting and clamping members may be shifted upon the bar 27, and the parts secured in their adjusted positions by merely manipulating a single screw.

Upon reference to Fig. 2, it will be seen that the gage arms are adjusted with reference to the dies so as to position a card 13 thereon, the card, when the dies are separated, being passed inwardly between the same and the rear edge thereof coming into contact with the vertically-disposed stop members 15 and 18; the under face overlying the members 16 and 19, and the right-hand edge of the card coming into contact with the vertically-disposed side gage finger 21. As will be readily appreciated, the gage arms may be adjusted so as to bring the card or sheet to be embossed into any desired relation with the embossing dies, and that once the gages are adjusted the operator may know that the embossing will take place upon the article at the desired point, if the card or other material be brought into proper relation with the stop fingers and the other members above referred to.

By having the bar 27 adjustable in the supporting member it will be readily appreciated that the gage arm 17 may be brought very close to the die, and the other gage arm, 14, carried to a considerable distance away from the die, or vice versa, which adjustments are advantageous when large sheets are being embossed.

Instead of employing the member 22, the construction shown in Figs. 5 and 6 may be used to support the gage. Under this construction it will be noted that the body of the press is provided with laterally-projecting hubs or ears 37, in which there is formed a squared opening through which the supporting bar 27 is passed and secured in its

lateral adjusted position by a wing nut 38. The hubs with the openings therein may be termed a supporting member for the bar 27.

Having thus described my invention, what I claim is:

1. A gage for use in conjunction with die presses comprising, in combination, a supporting member; a supporting bar carried by said member and adjustable endwise or in the direction of its length with reference to said member; and a pair of gage arms adjustably secured to said bar and extending forwardly into juxtaposition with the dies, whereby the material to be embossed will be properly positioned as it is inserted between the dies. 70

2. A gage for use in conjunction with die presses to properly position a card or sheet to be embossed by said press comprising, in combination, a supporting member; a bar carried by said member and extending laterally from each side thereof; a pair of gage arms; a combined supporting and clamping member for each gage arm, adjustably mounted upon the bar and in which the arms are adjustably mounted; and means for bringing the bar, arms and clamping members into clamping relation. 85

3. A gage for use in conjunction with a die press comprising, in combination, a supporting member; a bar adjustably mounted in said member and projecting laterally from each side thereof; a pair of gage arms adapted to position the sheet or card to be embossed with reference to the dies; and a combined clamp and supporting member for each arm, said member comprising a hooded structure provided with openings adapted to receive the bar and likewise to receive the rear end of the gage arm, and a screw overlying the arm and adapted to force the same into binding relation with the underlying bar. 95

4. A gage adapted for use in conjunction with die presses comprising, in combination, a supporting member, said member having a transversely-extending opening formed therein; a bar passing through said opening and extending to each side of the supporting member; means for securing said bar in its adjusted position with reference to the member; a pair of gage arms; and a clamping and sustaining element for each of said arms, said element comprising a sheet metal structure bent to form and having a top plate and four downwardly-extending side members, two of said members being provided with oppositely-disposed openings adapted to receive the end of the supporting bar, the opposite members likewise being provided with openings in a plane above those in the other sides and adapted to receive the end of the gage arm, said openings being made sufficiently large to permit vertical play or movement of the bar, and a screw mounted 110

115

120

130

in the upper member and adapted to force the arm downwardly into contact with the bar and to thus lock the parts together against movement in their adjusted relation.

5 5. A gage for use in conjunction with die presses comprising, in combination, a supporting member; a bar carried thereby; and a pair of arms so mounted upon said bar that they may be moved toward or from each other and projected forwardly or backwardly, one of said arms having at its forward end a downwardly-inclined stop and a forwardly-projecting finger, while the other arm is provided with a downwardly-extending stop member, a sustaining member, and an upwardly-projecting side gage or finger.

10 6. In combination with a die press, the body of which is provided with a trans-

versely extending opening; a bar adjustably mounted in said opening and extending laterally to each side of the press; means for clamping the bar in its adjusted position within said opening; and a pair of gage arms adjustably secured to said bar and extending forwardly into operative position 25 with reference to the dies and adapted to position the body to be embossed or printed both laterally and transversely with reference to the dies.

In testimony whereof I have signed my 30 name to this specification in the presence of two subscribing witnesses.

ALFRED WALTER ROOVERS.
